Attorney

UNITED STATES PATENT OFFICE.

EMIL DIETZ, OF INDIANAPOLIS, INDIANA. ASSIGNOR TO CARL V. DIETZ, OF INDIANAPOLIS, INDIANA.

CORNER IRON FOR TRUCKS.

Application filed June 23, 1923. Serial No. 647,836.

To all whom it may concern:

Be it known that I, EMIL DIETZ, a citizen of the United States, residing at Indianapolis, in the county of Marion and State 5 of Indiana, have invented certain new and useful Improvements in Corner Irons for Trucks, of which the following is a specification.

My said invention relates to a corner iron 10 for trucks and it is an object thereof to provide a simple and cheap device of the character indicated which can be applied to either a side or an end rail of a truck with little difficulty and with a minimum expense 15 in time and money.

Referring to the accompanying drawings, which are made a part hereof and on which similar reference characters indicate similar parts,

20 Figure 1 is a perspective of so much of a truck as suffices to show the location and construction of my improved device, and

Figure 2, a longitudinal section of the corner iron and the parts adjacent thereto.

25 In the drawings reference character 10 indicates a side rail of a truck and 11 an end rail, to which is secured the usual floor board or swivel board 12. My improved corner iron comprises a socket portion 13

30 and a pair of projecting arms 14 at one side of the same, these arms being bent toward one another at 15 so as to embrace a reduced part of the end rail 11. It will be seen that the end rail can be secured to the 35 side rail in any ordinary manner and that the corner iron will lie flat against the side rail but that no machine work on the side rail is necessary. When the corner iron is arranged to have its arms 14 embrace a part

40 of a side rail the body of the iron will rest against the end rail without the necessity of any machine work on such rail.

The corner iron of my invention is equally well fitted for fast or loose standards. A 45 loose standard will be supported on the floor board 12 while a fast standard will be fixed in place by a bolt passing through bolt holes

16 only one of which is shown in the drawing. If desired I may dispense with one of the ordinary bolt holes and drive a screw 50 through the adjacent rail and the single hole in the standard. A hole is also shown at 17 to receive a bolt passing through registering holes in the arms 14, the end rail 11 and the bottom board 12, and ears 18 are 55 provided at each side thereof to prevent rotation of the bolt. Another bolt hole is shown in dotted lines in Figure 2 at 19 by means of which the iron may be secured to the end rail by a horizontal bolt, the bolt 60 holes 16 and 19 being countersunk to provide smooth inner faces for the stake socket. It will be noted that each of these bolt holes is offset in such a manner that the bolts will not interfere with one another at any time. 65

Various minor changes will suggest themselves to those skilled in the art and therefore I do not limit myself to the precise structure shown in the drawings and described in the specification but only as indicated in the appended claim.

Having thus fully described my said invention, what I claim as new and desire to secure by Letters Patent, is:

A corner iron for trucks comprising a 75 body having a socket, a pair of horizontal arms extending respectively from the upper and lower ends of said socket at one side thereof adapted to engage over a rail, said arms having their ends inturned to embrace 80 said rail, said corner iron being adapted to be secured against the side and end rails and floor board of a truck to hold the parts securely in position, substantially as set forth.

In witness whereof, I have hereunto set my hand and seal at Indianapolis, Indiana, this 19th day of June, A. D. nineteen hundred and twenty-three.

EMIL DIETZ. [L. S.]
